UNITED STATES PATENT OFFICE.

CARL HANS VOM BAUR, OF DOUGLASTON, NEW YORK.

ELECTRIC FURNACE.

1,252,633.

Specification of Letters Patent.

Patented Jan. 8, 1918.

Application filed August 6, 1917. Serial No. 184,554.

To all whom it may concern:

Be it known that I, CARL HANS VOM BAUR, a citizen of the United States, and a resident of Douglaston, in the county of 5 Queens and State of New York, have invented certain new and useful Improvements in Electric Furnaces, of which the following is a specification.

My invention relates to electric furnaces, 10 and has for its object to provide a simple and efficient construction insuring a uniform or approximately uniform distribution of the current, or of the heat produced thereby. The form of my invention illustrated herein 15 and described in detail below, has especial reference to an electric furnace having an imperforate bottom and provided with electrodes connected with a two-phase, three-wire system of electric current distribution, 20 all combined so as to secure certain advantages specified hereinafter. Other features of the invention have reference to the adjustment of the electrodes, the shape of the furnace, and various novel arrangements explained below and particularized in the appended claims.

In the accompanying drawing:

Figure 1 is a vertical section on line 1—1 Fig. 2, showing a typical form of my improved electric furnace, with a diagram of its electrical connections;

Fig. 2, a plan view of the furnace, with the roof removed;

Fig. 3, a vertical section on line 3—3 Fig. 35 2; and

Fig. 4, an enlarged detail showing one of the adjustable electrodes.

At A, I have indicated a transformer whereby a polyphase current supplied 40 through three wires (say from an ordinary alternator) is converted into a two-phase current to be supplied through the three wires B, B¹, B², to the electrodes C, C¹, C², of the electric furnace. Of course, if a 45 three-wire, two-phase current giving the desired furnace voltage is available directly, the transformer A will not be required.

The electrodes pass through the top or roof D of the electric furnace, made of any 50 suitable refractory material. While preferably the electrodes are employed in a vertical position, arrangements may be provided for adjusting them or at least the lateral electrodes C, C², so that their lower ends 55 will be brought nearer to, or farther from the side wall E¹ of the furnace, which side wall

is generally made integral with the solid (imperforate) bottom E. The central electrode C¹ is preferably adjustable only up and down, so that it is always vertical. For 60 the purpose of such adjustment, the lateral electrodes pass through holders F of tubular structure, with washers G of asbestos or like material to secure the electrodes in the holders. These washers are required because a 65 direct fitting of the electrodes to the holders is impossible on account of the lack of uniformity in the diameter of the electrodes as made commercially. The holders F are made with surfaces F¹ of spherical curvature, seated in corresponding sockets at the outer ends of the roof openings through which the electrodes extend. Suitable rods or handles F² may project upwardly from the holders F, for adjusting them as desired. 70 Thus the upright electrodes may be given either a perfectly vertical position as shown on the left in Fig. 1, or one inclined in any direction, at the operator's choice, as shown on the right in Fig. 1. The electrodes are 75 also adjustable lengthwise in their holders F.

The furnace is provided with a discharge spout H (say at the middle of one of its sides), and with one or more doors J (say on the opposite side), for the purpose of 85 inspection, patching, charging, rabbelling off slag, etc.

With the two-phase, three-wire arrangement described, the two lateral electrodes C, C² receive like amounts of current, while 90 the central electrode C¹ (preferably of larger diameter than the others) receives a greater amount of current than either of the lateral electrodes, the ratio being as $\sqrt{2}$ to 1. Now, one of the features of my invention 95 consists in giving the side wall E¹ of the furnace such a shape with reference to the normal location of the electrodes, C, C¹, C², that the amounts of heat reaching the side wall when the mass within the furnace is 100 molten, will be approximately the same for every point of the contour of the side wall. For this purpose, as shown best in Fig. 2, the three electrodes are arranged normally 105 in the same plane, and the distances from the lower ends of the electrodes (when in their normal vertical position) to the respective nearest points of the side wall E¹, are exactly or approximately in the same ratio 110 as the amounts of current received by the respective electrodes; that is to say, if the distance from one of the lateral electrodes

C, C² to the nearest point of the wall E¹ is taken as 1, then the distance from the central electrode C¹ to the nearest point of the side wall E¹ will be $\sqrt{2}$, (slightly modified for the reason that the heat rays from all three electrodes converge.) The outline required theoretically would be two circular arcs at the middle of the furnace, having their common center at C¹ and $\sqrt{2}$ as their radius modified as described, these arcs being continued to their points of intersection, as indicated by dotted lines in Fig. 2. In practice, however, this shape is modified by placing between said circular arcs, straight wall portions which are preferably tangential to the respective arcs connected by them. With this arrangement, the distribution of the electric current and therefore the heating effect (temperature gradient) are practically uniform throughout the marginal portion of the furnace, and all portions of the outline or periphery of the side wall E¹ will be heated approximately to the same extent, thus avoiding uneven temperature strains.

In the operation of my improved furnace, it is intended to have the electrodes extended to the mass of material under treatment, so that the conducting molten bath will form part of the circuit between the electrodes.

It is by no means desirable or thought advantageous to operate the phases separately, nor to arrange the electrodes in such a way that the heat is generated between the tips of the electrodes only, without the aid of the bath as a conductor for reasons as hereinafter set forth.

The reason for not desiring the arc to be made only between the tips of the electrodes, which could be done by inclining the two lesser current carrying electrodes C, C², when arranged in a straight line, or nearly so, and keeping the middle heavier current carrying electrode C¹ vertical, is because this so-called "free burning" or flaming arc has been found detrimental to a prolonged life of the refractory materials in the side wall E¹ and the roof D. I do not wish the phases to be separate, since this would necessitate adding an electrode and would make the current unsteady on account of the lack of connection between the phases, and also since, in this case, each electrode only carries, other things being equal, the same amount of current, and, therefore, no predominately high current can be forced into a highly piled up mass of raw material to be treated directly beneath the center electrode.

My invention contemplates using, therefore, three electrodes all arranged vertically or nearly so, and adjustable not only in the line of their axes, but also at an angle so that cold corners of the metal, composition or other material to be melted, can be

reached by changing the position of one of the lesser carrying electrodes C, C² to an angle from the vertical. Furthermore, by placing the electrode C¹ carrying the geometrical sum of the currents of the other two, in the center of the furnace and over the cold material to be melted and treated, which is commonly piled higher in the center than near the ends of the furnace, I secure the manifest improvement of having more current where the charge is heavier. Later on, when the charge is molten, the heavier current and consequently greater heat of the electrode C¹ carrying the greater current, as before mentioned, will materially aid the circulation of the bath by making the part immediately beneath this larger current carrying electrode hotter than the parts of the molten bath beneath either of the other electrodes carrying lesser currents. This is particularly so, when the electrodes are arranged in a straight line, or nearly so, and this is the preferred construction of my invention. I do not, however, limit myself to placing the electrodes in this manner, and could place them in a position so that they would be equidistant from each other.

In prior constructions, the refractory side walls, particularly, have suffered severely from the radiated heat of the arc and it is the object with this construction to mitigate this as much as possible by having as one, and the preferable form of hearth, the shape of an oval as shown in the drawing so that the greater heat of the central electrode is farther away from the side walls than the lesser heat of either of the other two electrodes, and the heat from each electrode is practically proportional to the distance it is away from the side wall. Furthermore, this oval construction gives a greater area of the bath than a round form for the same holding capacity and consequently, other things being equal, the metallurgical treatment is hastened with my form of hearth or furnace, since the slag contact with the bath for an equal volume is greater and the refining of metals, such as iron or steel or the like, depends largely on the quantity of slag in contact with the metal to be treated.

In the form illustrated, my invention may therefore, be described as applied to an electric furnace of the arc type, the electrodes of which are specifically connected to mains supplied with poly-phase current, that is to the conductors of the low tension side of the transformer or alternator so that the two-phase currents are here supplied and then connected to the so-called two-phase, three-wire system, where the middle conductor carries the geometrical sum or amount of current or both of the other two conductors. The number of electrodes chosen is, therefore, three, and each elec

trode is so placed that the arc is between one end thereof and the material to be treated in the furnace. In this form, the main fluctuations will be found in the electric conductors and their directly connected electrodes C , C^2 carrying the lesser currents, consequently, the remaining electrode C^1 has fewer fluctuations, which is of decided advantage, not only in maintaining a more uniform heat in the furnace, but also in putting a lesser strain on the source of the electrical supply. The efficiency of the furnace is also increased since the heat gradient is the same in all parts of the furnace, (due to the position of the three vertical electrodes, when in one line or nearly so, placed in an oval shaped hearth, as herein mentioned) and because the heat is applied more uniformly even without the aid of extraneous means of automatic regulation of the electric heat.

I claim:

1. In an electric furnace, the combination of a two-phase, three-wire circuit, three upper electrodes connected to this circuit, a furnace having a solid bottom and an oval-shaped side wall of refractory material, said electrodes being so spaced that at the slag line the heat gradient is the same for each electrode at the point of the side wall which is nearest to such electrode.
2. An electric furnace whose outline, in plan view, comprises two end portions curved according to arcs of circles of equal radii but different centers, and two middle portions curved according to arcs of a circle of greater radius having its center in line with the centers of the other arcs.

3. An electric furnace whose outline, in plan view, comprises two end portions 40 curved according to arcs of circles of equal radii but different centers, two middle portions curved according to arcs of a circle whose radius is substantially $\sqrt{2}$ times the radius of either of the end arcs, and whose 45 center is in line with those of the end arcs, and tangential portions connecting the middle arcs with the end arcs.

4. An electric furnace whose outline, in plan view, comprises a plurality of circular 50 arcs having different centers, and electrodes located approximately at the centers of said arcs.

5. An electric furnace whose outline, in plan view, comprises two end portions 55 curved according to arcs of circles of equal radii but different centers, and two middle portions curved according to arcs of a circle of greater radius having its center in line with the centers of the end arcs, and electrodes located approximately at the centers 60 of said arcs.

6. An electric furnace whose outline, in plan view, comprises two end portions 65 curved according to arcs of circles of equal radii but different centers, two middle portions curved according to arcs of a circle whose radius is substantially $\sqrt{2}$ times the radius of either of the end arcs, and whose 70 center is in line with those of the end arcs, and electrodes located approximately at the centers of said arcs and adapted for connection with a two-phase, three-wire current supply.

CARL HANS VOM BAUR.
